DESIGN FOR A BIRTH DATA NAPKIN RING

Oscar A. von S. Buckow, Basking Ridge, N. J., assignor to Engraving and Engine Turning Co., Inc., Newark, N. J., a corporation of New Jersey

Application September 25, 1945, Serial No. 122,338

Term of patent 14 years

(Cl. D44—20)

To all whom it may concern:

Be it known that I, Oscar A. von S. Buckow, a citizen of the United States, residing at Basking Ridge, in the county of Somerset and State of New Jersey, have invented a new, original, and ornamental Design for a Birth Data Napkin Ring, of which the following is a specification, reference being had to the accompanying drawing, forming a part thereof.

In said drawing the figure is a perspective view of a birth data napkin ring, embodying my new design.

I claim:

The ornamental design for a birth data napkin ring, as shown.

OSCAR A. von S. BUCKOW.
